UNITED STATES PATENT OFFICE.

FREDERICK S. SPAULDING, OF DENVER, COLORADO, ASSIGNOR, BY DIRECT AND MESNE ASSIGNMENTS, TO THE SPAULDING MANUFACTURING COMPANY, OF BOSTON, MASSACHUSETTS, A CORPORATION OF MAINE.

GLIDING SWING.

957,855.

Specification of Letters Patent.

Patented May 10, 1910.

Application filed January 2, 1909. Serial No. 470,515.

To all whom it may concern:

Be it known that I, FREDERICK S. SPAULDING, a citizen of the United States, residing in the city and county of Denver and State 5 of Colorado, have invented certain new and useful Improvements in Gliding Swings; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention relates to improvements in gliding swings and comprises a structure having a relatively stationary base or platform, and a superstructure adapted to have an undulatory reciprocating movement. 20 This superstructure comprises a frame upon which chairs, or settees, or any suitable construction are mounted. The frame is provided with rollers or wheels adapted to engage the tracks with which the stationary 25 base is provided, the said tracks being downwardly curved between their extremities, whereby a wave-like or undulatory movement is imparted to the reciprocating member. In order to facilitate the movement of 30 the superstructure, a spiral spring connects the frame of the latter with the stationary base, the axis of the spring occupying a vertical position, when the gliding frame is in the normal or central position upon the base. 35 When this frame is moved in either direction, the spring is placed under tension and its recoil aids in imparting the reverse movement to the gliding frame.

Having briefly outlined my improved construction, I will proceed to describe the same in detail, reference being made to the accompanying drawing, in which is illustrated an embodiment thereof.

In this drawing, Figure 1 is a side elevation of my improved construction, one of the guard rails being partly broken away. Fig. 2 is a vertical longitudinal section of the apparatus. Fig. 3 is a top plan view of the relatively stationary platform. Fig. 4 45 is a section taken on the line 4-4 Fig. 1, looking toward the left. Fig. 5 is a fragmentary side elevation showing a portion of the stationary platform and of the gliding frame mounted thereon, the parts being

shown on a larger scale. Fig. 6 is a section 55 taken on the line 6-6 Fig. 5.

The same reference characters indicate the same parts in all the views.

Let the numeral 5 designate the relatively stationary base or platform composed of 60 parallel side beams 6 connected by transverse members 7, to which are secured slats 8 constituting a platform located between the beams 6. Each beam 6 is concave, as shown at 9, on opposite sides of its central 65 portion, and these concave parts are equipped with tracks 10, which are curved to conform with the concavities 9. To the outer surface of each beam 6 is secured a 70 guard rail 12, which projects above the beam and serves to prevent the possible lateral displacement of the gliding superstructure. These guard rails or plates also prevent children or others from getting injured by accidentally placing their feet or hands 75 upon the tracks in the path of the gliding structure.

The reciprocating superstructure supported by the base is composed of a frame 13 comprising parallel side rails 14 connected by cross bars 15. To the under surface of each rail 14 is secured a pair of brackets 17 in each of which is journaled a wheel or roller 16 adapted to engage one of the tracks 10. The side rails 14 are each 80 centrally connected with one of the beams 5 by a coil spring 18, one extremity of which is connected with a pin 19 fast upon the rail 14, while the other extremity is connected with a pin 20 fast upon a beam 5. 90

Upon the frame 13 are mounted chairs or settees 21, each of which is provided with front and rear legs 22 and 23, upon which is mounted a seat 24 having a back 25, side arms 26, and upwardly projecting front 95 arms 27. These chairs or settees may be of any suitable construction, and, therefore, need not be further described in detail.

When the superstructure is in use it may be assumed that one or more persons occupies each of the chairs 21, in which event they sit facing each other. In order to operate the swing, it may be assumed that a person in one of the chairs presses with his feet upon the platform 8, in such a manner 100 as to cause the frame 13 to move in one direction or the other from the central position illustrated in Fig. 1. The position after

such movement is illustrated in Fig. 2, in which the gliding frame is moved toward the left, whereby each roller 16 is caused to engage one extremity of the tracks 10. 5 When in this position, the spring 18 is placed under tension and its recoil has a tendency to impart the reverse movement. The movable structure also has a tendency to move toward the right by gravity, at least until 10 the rollers reach the lowest part of the track 10. When this occurs the momentum of the reciprocating member will cause the same to travel to its limit of movement toward the right. Hence, after the initial movement is 15 imparted to the gliding superstructure, but little if any effort upon the part of the occupants of the chairs will be necessary in order to keep the swing in motion. It is easy, however, for the persons in the swing 20 to keep it in motion by pressing occasionally with their feet upon the stationary platform, as heretofore explained.

Having thus described my invention, what I claim is:

25 1. The combination with a horizontal frame carrying one or more seats and supporting wheels rotatably secured beneath the same, of tracks for said wheels having certain parts thereof elevated above the remainder, and guard boards secured exterior to said tracks and rising a substantial distance above the same, whereby the feet of persons upon said seats or otherwise nearby can not be caught between the track and 30 35 frame when the latter is elevated, and be

crushed when said frame approaches its lowermost position in rolling back and forth on said uneven track.

2. The combination with a horizontal frame carrying one or more seats, and a vertically uneven pair of track-members, of brackets fixed to the under face of said frame and track-engaging wheels rotatably mounted in said brackets, the distance between the under face of said frame and the lowermost peripheral point of said wheels being in excess of the difference in level between the highest and lowest points of said tracks, and guard boards secured exterior to said tracks for the purpose set forth. 40 45 50

3. The combination with a horizontal frame carrying one or more seats and embracing longitudinal side-bars, of two brackets fixed to the under surface of each said side-bars, wheels rotatably mounted in said brackets, beams located beneath and parallel with said side-bars and having vertically uneven tracks in their upper faces engaging and supporting said wheels, and guard-boards secured to the outer surfaces of said beams and rising to a height substantially equal to that of the under surface of the side-bars when their supporting wheels are located on the highest parts of said tracks. 55 60

In testimony whereof I affix my signature 65 in presence of two witnesses.

FREDERICK S. SPAULDING.
